[57] **CLAIM**

The ornamental design for an electronic modular desk or similar article, as shown and described.

DESCRIPTION

FIG. 1 is a front perspective view of an electronic modular desk showing one embodiment of my design;

FIG. 2 is a rear perspective view of the desk shown in FIG. 1;

FIG. 3 is an end view of the desk shown in FIG. 1 with the opposite end being identical in appearance;

FIG. 4 is a perspective view of still another electronic modular desk only with other modular units assembled differently therewith;

FIG. 5 is a side view of the desk shown in FIG. 4 only showing the nonvisible side of the desk in FIG. 4; and

FIG. 6 is an end view of the desk shown in FIG. 4 and the opposite end is identical in appearance.

The bottom is plain and essentially unornamented, and

normally is not visible when in use.
